UNITED STATES PATENT OFFICE.

CLEBURNE L. HAYES, OF DE FUNIAK SPRINGS, FLORIDA.

PROGRAM-CLOCK.

SPECIFICATION forming part of Letters Patent No. 669,581, dated March 12, 1901.

Application filed June 19, 1900. Serial No. 20,878. (No model.)

To all whom it may concern:

Be it known that I, CLEBURNE L. HAYES, a citizen of the United States, residing at De Funiax Springs, in the county of Walton and 5 State of Florida, have invented a new and useful Alarm-Clock, of which the following is a specification.

This invention relates to alarm-clocks in general, and more particularly to that class 10 wherein the hands are utilized for closing the circuit of an electric alarm at predetermined intervals, the invention having specific reference to a clock for closing the circuit of an alarm or the circuits of several alarms to announce the times for performance of certain 15 acts or the terminations of certain periods, as where the periods of recitation and study in a school are arranged according to program.

20 A further object of the invention is to provide a construction wherein the sounding of the alarm will be of short duration, additional objects and advantages being evident from the following description.

25 In the drawings forming a portion of this specification, and in which like numerals of reference indicate similar parts in the several views, Figure 1 is an elevation of a clock-face and the hands thereof and showing the arrangement of the circuit-closer, the electric circuit to be closed being indicated diagrammatically. Fig. 2 is a rear elevation of the 30 hour-hand of the clock and the parts carried thereby, the contact-arm being shown engaged with a contact-pin and raised from its circuit-closing position. Fig. 3 is a partial section of the dial and hands of the clock and showing the connections of the hands to their 35 rotating shafts and the arrangement of the tension-changing eccentric and its co-operating strap. Fig. 4 is a section taken through a portion of the outer edge of the dial and adjacent parts and showing the manner of arranging the contact-pins. Fig. 5 is a section 40 taken through the pivoted block that carries the contact-arm.

45 Referring now to the drawings, the clock mechanism of the present invention is of common construction, as is also the dial 10, with the exception that the latter has an encircling ring of copper or other suitable metal 50 11 set flush therewith and insulated there-

from, and through this ring 11 are formed perforations 12, which are continued into the insulating-backing 13 of the ring and dial to 55 receive and hold removably a series of contact-pins 14, of suitable metal, these pins being disposed in radial alinement with the time-marks upon the dial which indicate the times when they are to be engaged by the 60 contact-arm hereinafter described.

An insulating-sleeve 15 is slipped over the shafts 16 and 17 of the clock and is fixed to the clock-face, and upon this sleeve is a metallic band 18, which is electrically connected with 65 one terminal of an electric battery 19 through a switch 20 and an alarm 21, the opposite terminal of said battery being electrically connected with the ring 11.

The minute-hand 22 of the clock is of usual 70 form and arrangement, while the hour-hand 23 carries a pivoted contact-arm, which is adapted for contact at times with the contact-pins 14 and with the band 18. This contact-arm (shown at 24) is mounted in an insulating-block 25, which is pivoted, by means of a screw 26, to a metallic block 27, held adjustably upon the extension 28 of the hour-hand by means of a set-screw 29. The contact-arm is adapted for adjustment longitudinally in the block 25 and is held in adjustment by a set-screw 30, said arm being of such length that it may touch a contact-pin 14 with its outer end and at the same time rest with its inner end upon the band 18 and 80 when in this position will close the circuit of the battery 19 to operate the alarm. 85

It will be noted that the arm 24 is mounted adjacent its outer end in the block 25, whereby a slight movement of the outer end of the 90 arm will result in a much greater movement of the inner end thereof, which rests upon the band 18, and thus as the contact-arm is carried around the dial of the clock by the hour-hand and is brought into contact with 95 a contact-pin 14 a very slight further movement of the hour-hand will move the contact-arm sufficiently to cause it to tilt and raise its inner end from contact with the band 18. Therefore while the contact-arm is in contact 100 with a contact-point for a relatively long time the circuit of the battery 19 is closed for only a very short percentage of that time. The utility of this arrangement will be ap-

parent when it is taken into consideration that for the purposes of the clock the circuit-closing contact-arm must be carried by the hour-hand and at the same time the duration 5 of the sounding of the alarm must not be so long as would be required for the hour-hand itself to rub against a contact-pin and close the circuit direct. The outer end of the contact-arm 24 is of hook shape, as shown, and 10 is of platinum or other refractile metal, although it will be understood that the end of the arm may have any specific form best suited to the conditions, the pivotal movement of the arm to raise its inner end from the 15 band 18 being limited by a guide 31, carried by the hour-hand, while the inner extremity of the arm has a platinum contacting tip.

Upon reference to Fig. 1 of the drawings it will be seen that the contact-arm will lie tangent to the lower half of the periphery of the band 18 during the progress of the hour-hand from twelve o'clock to six o'clock and that it will lie tangent to the upper half of the band during the remaining movement of the hour-hand. 25 Thus while some means must be provided for holding the inner end of the contact-arm yieldably against the band 18 at all times this holding means must be increased in its intensity during the time that the arm 30 is against the lower half of the band, for the reason that at this time the inner end of the arm tends to fall away from the under side of the band, as indicated in dotted lines in Fig. 1 of the drawings, due to the weight of the 35 long end of the arm. If the contact-arm is thus out of contact with the band, it will be tilted to where its outer end will not engage the contact-pins.

In order to hold the contact-arm normally 40 against the band 14 and in position to engage the contact-pins, a strap-spring 32 is provided, this spring having its outer end engaged with an eye carried by the block 25, while its opposite end is disposed in the end of an eccentric-rod 33, in which it is held by a set-screw 45. The eccentric-rod 33 forms a continuation of one end of an eccentric-strap 34, which engages a peripheral groove in a disk 36, of insulating material, which is mounted upon 50 the band 18 and eccentric thereto, said disk or eccentric being held against displacement by means of a set-screw 37, which is engaged therewith and is adapted for impingement against the surface of the band 18. The eccentric-rod 33 is slidably mounted in a guide-block 38, fixed to the back of the hour-hand, and which block, which is of insulating material, supports the guide 31. In practice the eccentric 36 is set so that its point of greatest 55 eccentricity will lie in the radius of the dial which passes through the numeral "3." Thus when the hour-hand leaves the numeral "12" the eccentric-strap moves to the right, moving the spring 32 or the inner end thereof outwardly, causing its central portion to bow and increase the tension of the spring to hold 60 the contact-arm more firmly against the band 65

18. The tension of the spring is thus increased to its maximum where the contact-arm has its greatest tendency to fall away 70 from the band 18, while the minimum tension of the spring is when the arm is at a diametrically opposite point.

It will be seen upon reference to Fig. 2 of the drawings that the ends of the eccentric-strap are connected by an adjustable screw 40, whereby the frictional engagement of the strap with the eccentric may be so gaged as to permit easy movement of the parts and yet prevent the eccentric-strap from slipping, 80 with resultant lost motion.

If desired, a number of bands 18 may be disposed one above another and separated by insulating material, and the perforations of the lower bands may be smaller than those of the upper bands, whereby contact-pins may be engaged with the lower bands and yet remain insulated from the upper bands. With this construction each band may govern a separate circuit, or, if desired, the band 18 90 may be in insulated segments, each segment governing a separate circuit, the several circuits being connected in multiple with a common source of electricity or having individual sources, as preferred. Furthermore, various other modifications of the specific construction shown may be made, and any suitable materials and proportions may be used for the various parts without departing from the spirit of the invention. 95

What is claimed is—

1. The combination with a clock and a hand thereof, of a pivoted contact-arm carried by the hand, a contact disposed for normal contact by the arm, a contact-pin in the path of movement of the contact-arm for engagement thereby to move it pivotally from the contact with which it is normally engaged, and an electric alarm-circuit including the pin and the contact with which the arm is normally engaged. 105

2. The combination with a timepiece, of a contact-arm pivoted to a hand of the time-piece, a contact-plate against which the arm normally rests, a contact-pin in the path of movement of the opposite end of the arm for engagement thereby to raise the arm from the contact-plate, means for holding the arm yieldably against the contact-plate, and an alarm-circuit having its terminals connected 115 with the pin and the contact-plate, respectively. 120

3. In a device of the class described, the combination with a movable member, of a contact-arm pivoted to the movable member, 125 a contact-plate against which the contact-arm normally rests, and a second contact in the path of movement of the pivoted arm with the movable member, to move the contact-arm from the contact-plate. 130

4. In a device of the class described, the combination with a rotatable member, of a contact-arm pivoted to the rotatable member, a contact-plate against which the con-

tact-arm normally rests, a contact-pin in the path of movement of the contact-arm to move the arm from the contact-plate, and variable means for holding the arm yieldingly against the contact-plate.

5. The combination with a clock, of a contact-arm pivoted to a hand thereof, an annular contact-plate against which the inner end of the arm normally rests, a contact-pin in the path of movement of the arm to move it pivotally from contact with the contact-plate, a spring disposed to hold the arm normally and yieldingly against the contact-plate, and means for varying the tension of the spring automatically.

10. The combination with a clock, of a contact-arm pivoted to a hand thereof, an annular contact-plate disposed concentric with the shaft of the hand and with which the contact-arm is adapted for normal contact to move over its periphery, a contact-point in the path of movement of the arm to move it from the annular plate, a spring connected with the arm to hold it normally and yieldingly in contact with the annular plate, a disk disposed eccentric to the shaft of the hand, a strap

slidably engaged with the periphery of the disk, and connections between the strap and spring for varying the tension of the spring.

15. The combination with a clock of a contact-arm pivoted thereto, an annular contact-plate disposed concentric with the shaft of the hand and against which the arm normally rests, a disk mounted upon the plate and eccentric thereto, a strap slidably engaged with the disk, a spring connected with the strap and arm to hold it normally in contact with the annular plate, a band having perforations, contact-pins adapted for engagement with the band to lie in the path of movement of the contact-arm for contact by the arm to move it from contact with the plate, and an alarm-circuit including the band and contact-plate.

20. In testimony that I claim the foregoing as my own I have hereto affixed my signature in the presence of two witnesses.
